(57) CLAIM

The ornamental design for a humidifier with fragrance, as shown and described.

DESCRIPTION

FIG. 1 is a perspective view of a humidifier with fragrance showing my new design:

FIG. 2 is a front elevation view thereof;

FIG. 3 is a top plan view thereof;

FIG. 4 is a left side elevation view thereof;

FIG. 5 is a rear elevation view thereof. The broken lines in the drawings illustrate features that form no part of the claim;

FIG. 6 is a right side elevation view thereof; and,

FIG. 7 is a bottom plan view thereof. The broken lines in the drawings illustrate features that form no part of the claim.
